UNITED STATES PATENT OFFICE.

OMER F. CHURCH, OF STEWARDSON, ILLINOIS.

ATTACHMENT FOR LATHES.

Application filed March 2, 1922. Serial No. 540,562.

To all whom it may concern:

Be it known that I, OMER F. CHURCH, a citizen of the United States, residing at Stewardson, in the county of Shelby and State of Illinois, have invented certain new and useful Improvements in Attachments for Lathes, of which the following is a specification.

This invention is an attachment for lathes intended more particularly for use in cutting key seats in shafts. One object of the invention is to provide a device which will operate efficiently and without the application of a high degree of power, and another object of the invention is to provide simple and efficient means whereby the cutting mechanism will be firmly supported and may be readily adjusted to meet the conditions of any particular piece of work. Other incidental objects of the invention will appear in the course of the following description.

The invention is illustrated in the accompanying drawings, in which—

Figure 1 is a perspective view of my improved attachment in position upon a lathe;

Fig. 2 is a central vertical section taken transversely of the driving shaft;

Fig. 3 is a detail horizontal section on the line 3—3 of Fig. 2;

Fig. 4 is a detail perspective view of a reinforcing bracket which may be employed in connection with the attachment;

Fig. 5 is a view showing in perspective the lower end of the cutter spindle and cutters which may be mounted thereon;

Fig. 6 is a detail view of the means for adjusting the device to set the cutter in a higher or lower position.

In the drawings, the reference numeral 1 indicates a portion of the bed of a lathe and 2 indicates a tool rest of the usual form which is supported upon the bed of the lathe and may be adjusted longitudinally and transversely thereof. Upon the tool rest 2,

45 I support a base 3 having a standard 4 rising from one edge and this base is secured to the tool rest in a set position by headed bolts 5 extending through the base into the shouldered channel 6 of the tool rest and

50 engaging a clamping plate 7 within the channel. The length of the clamping plate is nearly equal to the width of the tool rest and two or more bolts 5 are employed so that when the bolts are turned home the

55 base will be securely fastened and cannot turn upon the rest when the device is in

operation. The standard 4 is provided with a vertical slot 9 and on its rear side, at opposite sides of the said slot, is constructed with vertical ribs or guides 10. A gear housing 11 is supported on the standard 4 and is equipped on its front side with ribs or guides 12 which fit closely to the ribs 10, as shown most clearly in Fig. 3, so that, when the housing is being moved up or down, it will travel in a vertical rectilinear path. The upper end of the standard 4 carries a bearing or nut 8 in which is mounted an adjusting screw 13 provided with a hand wheel 14 at its upper end and having a circular head 15 at its lower end, said head being housed within a cap plate 15' secured upon the housing whereby a swiveled connection between the screw and the housing is effected. A stud bolt 16 is carried by the gear housing and passes through the slot 9 in the standard, a washer 17 being interposed between the head of the bolt and the face of the standard so that, when the bolt is turned home, the gear housing 80 will be clamped to the standard and securely supported. Loosening of the bolt will obviously, permit the housing to be adjusted vertically through manipulation of the screw 13 so that the cutter will be properly 85 centered with the shaft on which it is to act. The housing consists primarily of a U-shaped casting turned on one side and having its ends closed by plates or covers 18 which are rigidly secured thereto. The driving shaft 19 is supported in the side or cover plates 18, bushings 20 being fitted about the shaft to provide bearings therefor in the said plates 18. Between the bushings, a worm 21 is secured to the shaft, 90 and this worm meshes with a worm gear 22 which is secured in any desired or preferred manner to a spindle 23 which is disposed vertically in the rear ends of the housing 11 and may rotate in bushings 24 100 provided in the top and bottom of the housing. The lower portion of the spindle 23 is constructed with the annular seats 25 and 26 to either of which a cutter may be secured. The cutters are preferably disks 28 105 having cutter teeth 27 in their edges and they may be retained upon their respective seats in any desired manner. Inasmuch as a single cutting disk is not suitable for all classes of work and a disk of small diameter must necessarily have a central opening of relatively less diameter than a larger cutter, 110

it is necessary to provide a plurality of seats upon the cutter spindle. It is also necessary, to cut a key seat in a shaft in a proper manner, to have the cutter disposed upon a radius of the shaft in which the key seat is to be cut, as will be readily understood upon reference to Fig. 2, in which a relatively large cutter 28 is arranged to cut a seat in a shaft 29. The desired vertical adjustment of the cutter is obtained by adjusting the entire gear casing vertically so that a very slight shifting of the gear casing will bring the cutter into proper relation to the shaft upon which it is to act. In the same manner, a single cutter may be adjusted to work upon shafts of various diameters.

The driving shaft 19 projects beyond one side plate 18 to an extent sufficient to permit a band pulley 30 to be secured thereto. This pulley is constructed with annular flanges 31 so that the driving belt 32 will be received between the said flanges and will be thereby caused to travel with the attachment when it is shifted longitudinally of the lathe bed. The belt is driven in the usual manner from an overhead pulley as will be readily understood. The cutter is continuously rotated as the attachment is adjusted upon the bed lathe so that the cutter may be fed along the shaft as the cutting of the seat progresses and any desired length of seat produced.

I consider it advantageous and have found it sometimes to be necessary to reinforce the tool rest so that it will effectually withstand the strains placed thereon and will properly support the attachment. To this end, I employ a bracket consisting of a base plate 33 having a central opening 34 through which the bolt 5 may pass and a tool rest engaging arm 35 depending from the rear edge of the base plate 33, as shown at 36, so as to pass under and clear the lower end of the cutter spindle, the rear end of this arm being forked, as shown at 37, and terminating in claws or hooks 38 to engage the edges of the tool rest, as indicated in Fig. 2. This bracket adds very little to the weight of the attachment and very efficiently reinforces and braces the tool rest so that the weight of the gear housing 11 will not bend the retaining bolt 5 nor place breaking strain upon the tool rest.

The operation of my apparatus is thought to be evident from the foregoing description, and it will be readily noted that the driving gearing is almost entirely enclosed by the gear housing so that dust will not accumulate on the working parts and create

excessive wear thereon nor clog the operation. Moreover, the cutter is disposed below the gear housing so that the liability of the operator to be injured by contact with the cutter is minimized. The provision of worm gearing permits the cutter to be driven at the proper speed under a low power and also reduces the tendency of the opposed surfaces of the gearing to strip each other besides providing an even steady continuous movement of the cutter.

Having thus described the invention, what is claimed as new is:

1. A key seat cutting attachment for lathes comprising a support adapted to be secured upon the tool rest of a lathe, a gear housing secured to and projecting rearwardly from said support, a cutter spindle mounted vertically in the top and bottom of said gear housing and extending therethrough at the rear end thereof, a cutter secured upon the lower end of said spindle below the housing, a worm gear secured upon said spindle between the top and bottom of the housing, a driving shaft mounted in the sides of the housing and extending through the housing between the front end of the same and the spindle, a worm upon said shaft within the housing meshing with the worm gear, and means on one end of said shaft for rotating the same.

2. In a key seat cutting attachment for lathes, the combination of a support adapted to be secured upon the tool rest of a lathe and including a standard provided with a vertical slot and having an overhanging bearing at its upper end, a gear housing disposed adjacent the rear side of said standard and extending over the tool rest, interengaging guides on the opposed surfaces of the standard and the gear housing, a bolt carried by the housing and playing in the slot in the standard, an adjusting screw carried by the bearing at the upper end of the standard and having its lower end swiveled to the housing, and a cutter carried at the rear end of said housing.

3. The combination with a tool rest of a lathe, of a support adapted to be secured upon the tool rest, a gear housing carried by said support, a cutter carried by said housing, means for operating said cutter, and a bracket having a base plate fitting over the tool rest and under the said support, and an arm extending from said base and provided with a forked rear end adapted to engage the side edges of the tool rest.

In testimony whereof I affix my signature.

OMER F. CHURCH. [L. S.]
